UNITED STATES PATENT OFFICE.

GEORGE C. MURRAY, OF CHICAGO, ILLINOIS.

DRAFT-GEAR YOKE.

1,388,878.

Specification of Letters Patent. Patented Aug. 30, 1921.

Application filed December 11, 1919. Serial No. 344,004.

To all whom it may concern:

Be it known that I, GEORGE C. MURRAY, a citizen of the United States, residing at Chicago in the county of Cook and State of Illinois, have invented certain new and useful Improvements in Draft - Gear Yokes, of which the following is a specification.

This invention relates to improvements in draft gear yokes and its purpose is to provide 10 a yoke having an improved form of movable block for engaging a shoulder of the coupler butt. In the present form of the invention a movable block is provided at the forward end of the yoke and this block is 15 adapted to be tilted forwardly about its lower edge to a position wherein it engages the lower shoulder of the coupler butt, after which a key or bolt is inserted through the side walls of the yoke to retain the block 20 in its upright position. The various objects and advantages of the invention will appear more fully hereinafter.

The nature of the invention will be understood from the following specification 25 taken with the accompanying drawings in which one form is illustrated.

In the drawings—

Figure 1 shows a side elevation of the coupler butt and yoke with the forward end 30 of the yoke illustrated in vertical section on the line 1—1 of Fig. 4;

Fig. 2 shows a top plan view of the yoke with the forward end thereof illustrated in horizontal section on the line 2—2 of Fig. 1;

Fig. 3 shows a partial side elevation of the forward end of the yoke; and

Fig. 4 shows a vertical section through the shank of the coupler butt illustrating the forward end of the yoke in elevation.

The yoke 10 has upper and lower arms or walls 11 and 12, respectively, which are united at their rear ends by the integral rear wall 13. The upper and lower arms are united at their forward ends by integral 40 side walls 14 thus forming a hood or closure at the forward end of the yoke. The upper arm 11 terminates at its forward end in a transverse integral shoulder 15 adapted to coact with the shoulder 16 of the coupler butt 17. The lower surface of the coupler butt 17 is adapted to rest directly upon the lower wall 12 at the point 18. From the

point 18, the lower wall 12 is inclined downwardly and forwardly as shown at 19 and it then extends horizontally in a forward direction as shown at 20. The part 20 terminates in an upwardly directed transverse shoulder or flange 22 and the shoulder 22 terminates at its ends in upwardly directed lugs or flanges 23 which are formed 55 integrally with the side walls 14. The depression 21 which is formed beneath the coupler butt is adapted to contain a movable block 25 which is retained within the depression 21 during the insertion of the 60 coupler butt. The block 25 is substantially rectangular in cross-section but is rounded at its lower edge 25^a and is adapted to tilt upon the rounded surface which is formed 65 at the junction of the shoulder 22 with the 70 part 20 of the lower wall.

During the assembling of the yoke and coupler butt, the block 25 occupies a horizontal position resting on the part 20, as illustrated by the dotted lines in Fig. 1, and 75 the coupler butt is then tilted in a vertical plane by lowering the shank 17^a in order to permit the part to slide inwardly beneath the shoulder 15. After the coupler butt has been moved rearwardly to a position illustrated by the dotted lines in Fig. 1, the block 25 is tilted upwardly about its lower edge 80 until it seats against the shoulder 22 and the lugs 23. This movement of the block is conveniently effected by inserting a tool 85 through the aperture 27 which is formed through the part 20 adjacent the lower extremity of the inclined part 19. After being tilted upwardly, the block 25 is held in 90 its normal position by means of a key or bolt 28 of rectangular cross-section. The block 25 is provided adjacent the lower edge 95 with a longitudinally extending aperture 29 of rectangular cross-section and when the block is in its upright position, this aperture 29 is adapted to register with other apertures 30 which are formed through the side walls 14. The bolt 28 is then inserted until the head 28^a thereof engages one of the side walls 14 and a cotter pin 31, or the 100 like is passed through an aperture which is formed in the bolt 28 adjacent the other side wall 14. In this way the block 25 is held securely in its normal position and is

adapted to coact with the lower shoulder of the coupler butt when the latter is in its normal forward position. The coupler butt rests directly upon and is supported entirely by the lower wall of the yoke during the normal compression and expansion of the draft gear and the movable block 25 is relieved of all strains except the forwardly directed force imparted thereto by the coupler butt and transmitted thereby to the shoulder 22 and the lugs 23.

Although I have shown and described a single embodiment of the invention for purposes of illustration, it will be understood that it may be constructed in various other forms without departing from the scope of the appended claims.

I claim:

1. The combination with a yoke having upper and lower arms and a hooded forward end, of a drawbar having a shouldered butt adapted to be received within said hooded end, means carried by one of said arms to engage one shoulder of said butt, a movable block mounted adjacent the other arm and adapted to be tilted upwardly and forwardly about its lower edge into a position to engage the other shoulder of said butt, and means passing through said block and through the walls of said hooded ends to prevent a reverse tilting movement of said block.

2. The combination with a yoke having upper and lower arms and a hooded forward end, of a drawbar having a shouldered butt adapted to be received within said hooded end, means carried by one of said arms to engage one shoulder of said butt, a movable block mounted adjacent the other arm and adapted to be tilted into a position to engage the other shoulder of said butt, and a bolt adapted to form a non-rotatable engagement with said block and with the walls of said hooded end in the axis of the tilting movement of said block to hold said block in butt-engaging position.

3. The combination with a yoke having upper and lower arms and side walls forming a hooded forward end, of a drawbar having a shouldered butt adapted to be received within said yoke, a flange carried at the forward end of said upper arm to engage the upper shoulder of said butt, a second flange carried at the forward end of said lower arm, a block adapted to rest upon said lower arm beneath said butt during the insertion of said butt into said yoke and to be tilted into a position against said second-named flange after said butt has been inserted, and a key passing through said block in the axis of its tilting movement and through the said side walls.

4. The combination with a yoke having upper and lower arms and side walls forming a hooded forward end, of a drawbar having a shouldered butt adapted to be received

within said yoke, a flange carried at the forward end of said upper arm to engage the upper shoulder of said butt, a second flange carried at the forward end of said lower arm, a block adapted to rest upon said lower arm beneath said butt during the insertion of said butt into said yoke and to be tilted into a position against said second-named flange and wholly in front of the drawbar butt after said butt has been inserted, and a key passing through said block and through the said side walls, said butt being adapted to rest directly upon said lower arm, said lower arm being offset downwardly beneath the forward end of said butt.

5. The combination with a yoke having upper and lower arms and side walls forming a hooded forward end, of a drawbar having a shouldered butt adapted to be received within said yoke, a flange carried at the forward end of said upper arm to engage the upper shoulder of said butt, a second flange carried at the forward end of said lower arm, a block adapted to rest upon said lower arm beneath said butt during the insertion of said butt into said yoke and to be tilted into a position against said second-named flange after said butt has been inserted, said block having a longitudinal aperture therethrough adjacent its lower edge, said side walls having apertures adapted to register with the aperture in said block, and a bolt adapted to form a non-rotatable engagement with said apertures.

6. The combination with a yoke having upper and lower arms and side walls forming a hooded forward end, of a drawbar having a shouldered butt adapted to be received within said hooded end, a flange carried at the forward end of said upper arm to engage the upper shoulder of said butt, a second flange carried at the forward end of said lower arm, a block adapted to underlie said butt during the insertion of said butt into said yoke and to be tilted upwardly and forwardly about its lower edge until it seats against said second-named flange, said block in said last-named position being adapted to engage the lower shoulder of said butt, said block having longitudinal apertures therethrough adjacent its lower edge, said side walls having apertures therethrough adapted to register with the aperture in said block, all of said apertures being of non-circular cross-section, and a bolt adapted to fit all of said apertures.

7. The combination with a yoke having upper and lower arms and side walls forming a hooded forward end, of a drawbar having a shouldered butt adapted to be received within said hooded end, a flange carried at the forward end of said upper arm to engage the upper shoulder of said butt, a second flange carried at the forward end of said lower arm, a block adapted to rest upon said

lower arm beneath said butt during the insertion of said butt into said yoke and to be tilted into position against said second named flange after said butt has been inserted to engage the lower shoulder of said butt, and a key passing through said block in the axis of its tilting movement and en-

gaging the side walls of said yoke, said key being adapted to hold said block in either operative or inoperative position.

In testimony whereof, I have subscribed my name.

GEORGE C. MURRAY.
